To all to whom these presents shall come,

Greetings.

Notifying that the annexed true copy of a Patent granted to Michael Wither on the 24th of August 1823 for his improvement in the Mill-Brayon.

The testimony whereof of Henry Clay, Secretary of State of the United States, has hereto subjoined my name and caused

the Seal of the Department of State to be affixed

Done at the City of Washington this seventh day of March A.D. 1827, and of the Independence of the United States of America the 51st. H. Clay.

The Schedule referred to in these Letters Patent and making part of the same containing a description in the words of the said Michael Wither himself of his improvement in the Mill-Brayon.

These Brayons are made of cast iron and consist of a gudgeon with three or more wings that start from the gudgeon at an equal distance from each other and project outwards from the inside to the feet according to the beigness of the shape said projecting wings are bevelled towards the neck of the Brayon, and they also bevel in their thickness on the same side. these bevels are for the purpose of lightening the loops to prevent the Brayon coming out, and making the whole fast together it is then fixed to the end of the Mill-Shaft and is fit for operation. Said Brayon can be applied to all kinds of work or machinery where it may be found useful.

Withers

James H. Blister

And Wm. Parry

Michael Wither
